UNITED STATES PATENT OFFICE.

JACOB SINGER, OF NEW YORK, N. Y., ASSIGNOR TO HIMSELF, BENSON M. FELDMAN, AND ISAAC B. CASSEL, OF SAME PLACE.

SIPHON.

SPECIFICATION forming part of Letters Patent No. 465,734, dated December 22, 1891.

Application filed June 30, 1891. Serial No. 397,984. (No model.)

To all whom it may concern:

Be it known that I, JACOB SINGER, of New York city, in the county and State of New York, have invented a new and Improved 5 Siphon, of which the following is a full, clear, and exact description.

The object of the invention is to provide a new and improved siphon which is simple and durable in construction, very effective 10 and automatic in operation, being at all times ready for drawing liquids without requiring pumping or refilling for starting the device.

The invention consists of a bent tube provided at each end with a head adapted to 15 form a liquid seal for the ends of the tube.

The invention further consists of a faucet arranged in the discharge-head and serving to draw off the liquid, the other or inlet head being perforated above the end of the tube 20 to admit the liquid to the head and tube.

The invention also consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of the improvement with parts in section and as applied. Fig. 2 is a side elevation of the inlet-head and part of the tube, and Fig. 3 is a sectional plan view of the same on the line xx of Fig. 2.

The improved siphon is provided with the usual tube A, bent in U form, as is plainly shown, and provided at one end with a discharge-head B and at its other end with an inlet-head C. The discharge-head B is formed of a closed vessel secured to the outer end of the tube A, and arranged in such a manner that the end of the tube extends a short distance above the bottom of the vessel. In the wall of the latter is arranged a faucet D, of any approved construction, having its inlet above the lower end of the tube. The other head C is formed in the shape of an open vessel, having perforations E in its side walls, and a neck F, adapted to fit closely on the inner end of the tube A. The perforations E

are located above the lower end of the tube 50 A within the said head C, for the purpose hereinafter more fully described.

On the neck F is secured a hook G, adapted to engage part of a ring H, secured on the tube A, so as to support or lock the head C 55 in position on the end of the tube. It is understood that the hook G, in order to engage the ring H, is passed through the opening H', formed at the ends of the ring, after which the head is turned so as to engage the hook 60 with the top of the ring, as is plainly illustrated in Figs. 2 and 3.

On the middle part of the tube A is secured a ring I for conveniently hanging up the device when not in use. On the inlet end of 65 the tube A is fitted to slide a bung J, adapted to engage the bung-hole in the keg or barrel, so as to support the siphon in the proper position. A set-screw or other means may be employed on the bung J for fastening the tube 70 in place when adjusted.

The device is used as follows: In order to charge the tube A for continuous or intermittent use the head C is removed and the tube A is placed in an upside-down position 75 with the faucet D open. The tube is then filled with a liquid similar to the one to be drawn, the filling being accomplished through the inlet end of the tube. After this has been done the faucet D is closed, the head C is placed 80 on the inlet end of the tube in the manner above described, and then the tube A is turned over to assume its natural position. By so doing liquid seals are formed at the ends of the tube within the heads B and C, so that 85 air cannot penetrate into the tube, and at the same time the liquid within the tube cannot escape through either end. When the inlet end is now placed into the liquid to be drawn, as shown in Fig. 1, then the liquid within the 90 barrel can pass through the perforations E into the head C to completely fill the same. Now when the operator opens the faucet D, the siphon is started as the air-pressure on the liquid in the barrel forces the liquid into 95 the head C through the tube A into the head B, and from the latter through the faucet D to the outside. When the desired quantity

of liquid has been drawn off, the operator closes the faucet D, so that the head B, as well as the head C, remains filled, the latter up to the perforations E, in case the siphon 5 is withdrawn from the barrel. The siphon, with the charging-liquid, can now be conveniently hung up by the ring I until further use. As the liquid forms a seal for both ends of the tube in the heads B and C, the tube A 10 remains charged with the liquid. When the operator desires to again use the siphon, he simply passes the inlet end with the head C into the liquid and opens the faucet D, so that the liquid again flows through the latter 15 in the manner above described. Thus it will be seen that when the tube A is once filled it is always ready for use, no pump or other device being required to charge the tube for each operation. It will further be seen that 20 no suction-tubes or suction of the tube A is required in order to start the siphon.

Having thus described my invention, I claim as new, and desire to secure by Letters Patent—

- 25 1. A siphon comprising a bent tube, an inlet-head formed of a vessel apertured and secured to one end of the tube, and a discharge-head formed of a vessel secured to the other end of the tube, substantially as described.
- 30 2. A siphon comprising a bent tube, an inlet-head formed of an apertured vessel secured to one end of the tube, and a discharge-head formed of a vessel secured to the other end of the tube, the said tube projecting into 35 the heads to within a short distance of the bottoms thereof, substantially as described.
- 35 3. A siphon comprising a bent tube, and a head at each end of the tube, the heads being so arranged as to contain liquid and form a seal for the ends of the tube, and a faucet arranged in the discharge-head, substantially 40 as shown and described.
- 40 4. A siphon comprising a bent-tube, an inlet-head arranged on one end of the tube and 45 formed with perforations above the ends of the tube and arranged to contain liquid to

form a seal for this end of the tube, substantially as shown and described.

5. A siphon comprising a bent tube, an inlet-head arranged on one end of the tube and 50 formed with perforations above the ends of the tube and arranged to contain liquid to form a seal for this end of the tube, and a discharge-head held on the other end of the tube and also adapted to contain liquid to 55 form a seal for the outer end of the tube, substantially as shown and described.

6. A siphon comprising a bent tube, an inlet-head arranged on one end of the tube and formed with perforations and arranged to 60 contain liquid to form a seal for this end of the tube, a discharge-head held on the other end of the tube and also adapted to contain liquid to form a seal for the outer end of the tube, and a faucet arranged on this head and 65 having its inlet-opening above the lower end of the tube in the outlet-head, substantially as shown and described.

7. A siphon comprising a bent tube, a closed vessel arranged on the discharge end 70 of the tube and having its bottom below the lower edge of the said end, and an open vessel held on the inlet end of the tube and formed with perforations located above the lower edge of the inlet end of the said tube, sub- 75 stantially as shown and described.

8. A siphon comprising a bent tube, a closed vessel arranged on the discharge end of the tube and having its bottom below the lower edge of the said end, an open vessel 80 held on the inlet end of the tube and formed with perforations located above the lower edge of the inlet end of the said tube, and means, substantially as described, for attaching the said perforated vessel on the inlet end 85 of the tube, substantially as shown and described.

JACOB SINGER.
